COMBINED BOTTLE CAP AND LIPSTICK CASE

Morton Edell, Newark, N.J., assignor, by mesne assignments, to Hazel Bishop, Inc., Newark, N.J., a corporation of New York

Filed Aug. 16, 1961, Ser. No. 66,375

Term of patent 14 years

(Cl. D58—26)

FIG. 1 is a front elevational view of a combined bottle cap and lipstick case, showing my new design;

FIG. 2 is a top plan view thereof; and

FIG. 3 is an exploded side elevational view thereof, the side not shown being substantially the same.

The broken lines are only for illustrative purposes. The fragmentary showing of the bottle in FIG. 3 is for the convenience of illustration.

I claim:

The ornamental design for a combined bottle cap and lipstick case, substantially as shown and described.
